UNITED STATES PATENT OFFICE

JOHN W. MESHKO, OF ARROCHAR, STATEN ISLAND, NEW YORK, ASSIGNOR, BY MESNE
ASSIGNMENTS, TO JAMES KORNEY, OF NEW YORK, N. Y.

DESIGN FOR A CLASP

Application filed September 10, 1932. Serial No. 44,801. Term of patent 7 years.

To all whom it may concern:

Be it known that I, JOHN W. MESHKO, a citizen of the United States, residing at Arrochar, Staten Island, New York, in the county of Richmond and State of New York, have invented a new, original, and ornamental design for a clasp, of which the following is a specification.

In the accompanying drawing:—

Fig. 1 is a plan view of a clasp showing my new design.

Fig. 2 is an edge elevational view of Fig. 1.

In bottom view the clasp is identical to the showing of Fig. 1.

I claim:—

The ornamental design for a clasp as shown and described.

In testimony whereof I affix my signature.

JOHN W. MESHKO.
